ULTRA SHORT WAVE CONNECTION SYSTEM

Kurt Schlesinger, Berlin, Germany, assignor to
 Radioaktiengesellschaft D. S. Loewe, Berlin-
 Steglitz, Germany

Application November 20, 1935, Serial No. 50,737
 In Germany November 24, 1934

5 Claims. (Cl. 250—27)

- It is usual in the radio art to block the direct potential leads to the tube connections against earth or the cathode by means of blocking condensers, whereby these condensers together with any resistances or chokes in the lead circuit have the object of filtering the direct potentials in respect of hum and other ripples. In this connection it is always taken for granted that the points of the lead thus "blocked" are earthed also in respect of the radio frequencies. This assumption is also correct in radio apparatus of the usual kind in its application to radio waves of ten meters or more. When employing wavelengths of less than 10 metres, however, new difficulties arise owing to the fact that the blocking condensers usual in the art, which are of the order of approximately 1 mf., are in no way capable of effectively short-circuiting the lead for high-frequency currents. Even leads of not more than 5 cm. in length effect interferences in the reception, because the electrodes of the tube connected to the ends of these short wires are no longer to be regarded as being earthed, and that these leads form with the appendant capacities and their own self-induction well definite oscillatory circuits which may become resonant in the middle of the reception range. These interferences have been particularly noticeable in the ultra-short wave superheterodyne receivers for television reception.
- The present invention relates to the use of means to keep-off high-frequency interferences from the grid circuits of the single valves in ultra-short wave circuit arrangements and in accordance with the invention said means consisting in a condenser and a resistance are arranged in close proximity to the grid to be short-circuited, said condenser connecting the grid in the shortest way to the cathode of the tube in question and said resistance connecting the grid in question to the hum-preventing device used in said circuit arrangement.
- The invention will be clearly understood by way of exemplary embodiments shown in the accompanying drawing wherein
- Fig. 1 shows a special circuit arrangement in accordance with the present invention using a mixing tube with eight electrodes.
- Fig. 2 shows a special embodiment of the condenser and the resistance unit.
- In Fig. 1 there is shown a circuit arrangement using a mixing stage tube with eight electrodes, in which the receiving circuit 1 is connected with the inner grid 2 of the mixing system, and should be completely decoupled from the occurrences in the oscillatory system 4, 5 by a screening grid 3.

The earthing or blocking of the screening grid 3, as usual in the radio art for longer waves, is performed by means of a blocking condenser 6 of 1 mf., which is dimensioned together with a steady-resistance 8 for filtering against hum in the mains. It has been found in practice that, when using ultra-short waves, at quite definite frequencies, the apparent inductance 9 of the lead to the screening grid formed together with the apparent earth capacity 10 of the screening grid a 10 rejective circuit, and at this frequency the grid 3 is no longer to be considered as being earthed. In consequence at this frequency the oscillation of the mixing grid 11, which is connected with 4 and has the frequency of the oscillatory circuit 7, 15 passes through the medium of the grid 3, which is no longer a screening grid, to the input circuit, and causes there the above cited disturbances.

That which has been stated hereinafter regarding the lead to a screening grid also applies, however, as experiments of the applicant with ultra-short wave superhets have shown, quite generally to other earth leads which are required to carry any oscillatory potential. For example, every grid bias lead situated within the range of a short-wave oscillator, for example the line 12, is able to form in conjunction with the unavoidable apparent capacity 13 a resonance circuit, even if it is only a few centimetres in length and is closed off or dehummed at its battery end by a blocking 20 condenser 14, which from the point of view of the normal long-wave art is generously dimensioned, and a series resistance 15. All of these defective earth connections make themselves apparent in 25 practice by the occurrence of selective defects in 30 reception.

The object of the invention consists in the fact that the means for earthing a certain terminal of the ultra-short wave connection system is separated fundamentally from the means for eliminating hum and the filtering of the direct current. For the ultra-high frequency earthing there is employed a special earthing means, the connection of which is described in the following. It should establish a connection of such a nature between the points to be precluded from oscillation that its inner resistance remains sufficiently small in respect to the operating frequency to render reaction couplings by way of its resistance practically wholly impossible.

It is not required of the earthing means that the same plays any part in the low frequency filtering, for example for eliminating hum. The earthing means is, in accordance with the invention, provided at all points which are intended to 50 55

be "earthed" in respect of high frequency, and in which, in the case of very short waves, there is a suspicion of insufficient earthing owing to excessive impedance of the leads. As experience gained by the applicant has shown, a suspicion of this kind with waves of less than 10 metres in length is well founded when the leads are more than 5 cm. in length, particularly if these leads are disposed over earthed metallic plates, in which case an appreciable self-induction may be assumed, and particularly in the case of two-pole connections with double conductors.

In Fig. 1 an earthing means 16, 17 in accordance with the invention is provided in the screening grid lead 20. The earthing condenser 17 is connected in direct fashion with the tube connection system, by means of such short leads, and is itself so dimensioned, that the circuit formed by the leads and the by-pass condenser has a higher natural frequency than the ultra-high frequencies occurring. Particularly when using centimetre waves it may, for example, be necessary to fit the blocking condenser in the tube itself in order that the lead circuit will have a sufficiently short wave. The size of 17 requires to be merely approximately 100 to 500 cm.

There is associated with the earthing means 17 the series resistance 16, which is intended to prevent reaction couplings, which act on the connected lead 9 and are represented symbolically by a counter-inductance 18 or a part-capacity 19, from being able to act on the screening grid 3. The series resistance 16 accordingly renders harmless any errors in assembly which have been made in the feed line 9, 8 and which, if 16 were missing, would be able to lead to the stated interferences in operation despite the earthing condenser 17. The resistance 16, therefore, requires to be large merely in relation to the alternating resistance of 17. Since it may also be ignored as regards the D. C. circuit its resulting size may be 1000 to 500 ohms. The use of a choke is also possible, but is not equivalent to the aperiodic connection, since the same, as well known, has resonance points. The effectiveness of 16 is rendered doubtful if the lead 20 has a detrimental impedance between 16 and condenser 17. 16 and 17 are accordingly disposed in close proximity to each other and to the point to be earthed. The arrangement of the earthing means according to the invention for eliminating interference in the circuit of grid 2 is represented in Fig. 1 by the condenser 21 and the series resistance 22.

An arrangement which is known per se, but offers particular advantage in the present connection, is obtained according to Fig. 2 when the rod resistance 16, which may be formed itself in known fashion by a helical coating, has wound about it the condenser 17, the inner armature 17a of the condenser being directly connected with the point to be protected and the outer armature 17b with the earthing point, for example the cathode of the tube, and the point 30 connected with the bias line.

In lieu of a series resistance 16 in the form of a highly ohmic rod the lead may also be made as resistance wire. The use of distributed ohmic resistance of this kind offers advantages exactly in the case of ultra-short waves because concentrated resistances may easily be made ineffective by bridging capacities, whilst the execution of a longer lead as damping means offers a greater guarantee against the effectiveness of the damping, as at least always part-ranges of this lead will act as damping means. On the other hand

a resistance of approximately 30-50 ohms, which may already be obtained with technically available resistance wires with a length of line amounting to 5 cm., will be sufficient to deprive a circuit of its oscillatory character. It would accordingly be possible, for example, to make the line 9 or 12 of a resistance wire of approximately 250 ohms per metre or more, and then dispense with the resistance 16 or 22.

The improved system of earthing as applied here to a mixing hexode may naturally also be employed in conjunction with connection and coupling elements. It is of advantage in those cases in which ultra-short wave potentials seek to penetrate via the feed lines into the coupling element. For example, ultra-high frequency from the anode line 25 may penetrate via a choke coupling 23 to the grid of the next tube 24. When using the earthing element 26, 27 it is then merely necessary to consider the selection of the earthing point 28. It is desirable in every case to connect the earthing condenser 27 by the shortest way with the cathode of the tube to be protected. The connection of the high-frequency earthing means differs also in this respect from the connection of the steadyng condenser. The steadyng condensers may be connected to the frame work of the set whilst the high-frequency earthing means requires to be connected in every case to the cathodes of the single amplifying tubes, the coupling circuit or screening grid of which it protects, even if these cathodes belong to other circuits and do not require to be directly connected, either statically or dynamically, with the earthing mass, for example the chassis of the receiver.

I claim:

1. In an ultra-short wave apparatus comprising a vacuum tube having at least one grid and a cathode and a hum preventing device means to keep-off high-frequency interferences from the grid of said tube, said means consisting in a condenser and a resistance arranged in close proximity to said grid, said condenser connecting the grid in the shortest way to the cathode of said tube and said resistance connecting said grid to said hum preventing device.

2. In an ultra-short wave apparatus comprising a vacuum tube having at least one grid and a cathode and a hum preventing device, means to keep-off high-frequency interferences from the grid of said tube, said means consisting in a condenser and a resistance arranged in close proximity to said grid, said condenser connecting the grid in the shortest way to the cathode of said tube and said resistance connecting said grid to said hum preventing device, said condenser circuit between grid and cathode being tuned to a frequency not lower than that of said apparatus.

3. In an ultra-short wave apparatus comprising a vacuum tube having at least one grid and a cathode and a hum preventing device, means to keep-off high-frequency interferences from the grid of said tube, said means consisting in a condenser and a resistance arranged in close proximity to said grid, said condenser connecting the grid in the shortest way to the cathode of said tube and said resistance connecting said grid to said hum preventing device, said condenser and said resistance being combined in a unit, said condenser being wound upon said resistance, said resistance being in the form of a rod.

4. In an ultra-short wave apparatus comprising a vacuum tube having at least one grid and a cathode and a hum preventing device means to keep-off high-frequency interferences from the

grid of said tube, said means consisting in a condenser and a resistance arranged in close proximity to said grid, said condenser connecting the grid in the shortest way to the cathode of said tube and said resistance connecting said grid to said hum preventing device, said condenser and said resistance being combined in a unit, said condenser being wound upon said resistance, said resistance being in the form of a rod, said condenser circuit being tuned to a frequency not lower than that of said apparatus.

5. In an ultra-short wave apparatus comprising a vacuum tube having at least one grid and a

cathode and a hum preventing device, means to keep-off high-frequency interferences from the grid of said tube, said means consisting in a condenser and a resistance arranged in close proximity to said grid, said condenser connecting the grid in the shortest way to the cathode of said tube and said resistance connecting said grid to said hum preventing device, said condenser circuit between grid and cathode being tuned to a frequency not lower than that of said apparatus, 10 and arranged inside said tube.

KURT SCHLESINGER.
